[57] **CLAIM**

The ornamental design for an array of heater modules in a food service cart, as shown and described.

DESCRIPTION

FIG. 1 is a front elevational view of an array of heater modules in a food service cart showing our new design; FIG. 2 is a side elevational view thereof;

FIG. 3 is a top plan view thereof;

FIG. 4 is a bottom plan view thereof;

FIG. 5 is a top plan view of a second embodiment of the array of heater modules in a food service cart, the bottom view being the same as the first embodiment shown in FIG. 4;

FIG. 6 is a top perspective view of FIG. 3; and,

FIG. 7 is a top perspective view of FIG. 1.

The broken lines shown in FIGS. 1 through 7 are for illustrative purposes only and form no part of the claimed design.

FIG. 1.**FIG. 2.****FIG. 3.****FIG. 4.****FIG. 5.****FIG. 6****FIG. 7**
